SAW-TOOT WAVE GENERATOR

Reuben Lee, Linthicum Heights, Md., assignor to
Westinghouse Electric Corporation, East Pittsburgh, Pa., a corporation of Pennsylvania

Application September 12, 1946, Serial No. 696,574

5 Claims. (Cl. 178—44)

1

My invention relates to oscillation generators and, in particular, to a new type of oscillation generator particularly adapted to the production of sawtooth wave forms.

One object of my invention is to produce a generator for sharply peaked waves which shall be of a high degree of stability in respect to frequency and amplitude.

Another object of my invention is to provide a generator of waves of the general sawtooth form which shall involve only relatively simple circuit elements.

Another object of my invention is to provide a generator for sawtooth waves in which the wave-slope is to a high degree rectilinear.

Still another object of my invention is to provide an arrangement for generating sawtooth waves which shall employ only alternating-current generators of substantially pure sine waves in combination with a circuit involving rectifiers.

A further object of my invention is to provide a sawtooth wave generator the output of which shall have a wave form of substantially linear negative slope.

Other objects of my invention will become apparent upon reading the following description taken in connection with the accompanying drawings, in which:

Figures 1, 2, 6 and 7 are graphs showing the wave form produced by certain circuits embodying the principles of my invention;

Fig. 3 is a circuit diagram of an embodiment of my invention; and

Figs. 4, 5, 8 and 9 are diagrams of certain circuit networks which may be employed in carrying out the principles of my invention.

Fig. 10 is a circuit diagram combining the network of Fig. 8 with the voltage source of Fig. 3.

Referring in detail to the drawing, the curve marked e_1 in Fig. 1 shows a plot in which the abscissae represent time and the ordinates amplitude of the output voltage of an ideal full-wave rectifier when the input voltage thereto is an ideal pure sine wave. In order to obtain an output voltage of the form e_1 it is necessary that the circuits of the rectifier shall have the least practicable leakage inductance and stray capacitance.

The curve e_2 in Fig. 1 is simply the reverse of the curve e_1 displaced slightly in phase relative thereto; in other words, it illustrates the wave form of the output of a similar full-wave rectifier so connected as to produce current of the opposite polarity to the rectifier producing the curve e_1 , and supplied from a sine wave alternator which

2

lags slightly in phase relative to that supplying the rectifier of output e_1 .

When the ordinates of the curves e_1 and e_2 of Fig. 1 are added together, a curve of the wave form e_3 shown in Fig. 2 results. It will be noted that in Fig. 2 the downward slope of the curve is not exactly rectilinear, but that the curve gives a fair approximation to a sawtooth wave. Varying the phase displacement between the curves e_1 and e_2 will change the amount of the departure of the down-slope from rectilinearity and will also change the amplitude of the peaks and troughs of the wave, and the ratio of up-slope to down-slope. However, the curve e_3 in Fig. 2 probably represents about the best approximation to a rectilinear down-slope that can be obtained, with the phase displacement between curves e_1 and e_2 such as to give steep up-slope.

A circuit network capable of producing voltage of the wave form e_3 is shown in Fig. 3 where an ordinary high vacuum triode 1 has its plate circuit provided with an anti-resonant tuned network comprising an inductance 2 and a capacitance 3 and likewise has its grid circuit provided with a self-bias circuit comprising a resistance 4 and a capacitance 5. In a manner well known in the electronics art, the grid circuit and the plate circuit of the tube 1 are magnetically inter-linked, for example, by locating the inductance 2 and an inductance 6 in the grid circuit in mutually inductive relation to each other. The circuit 1 to 6 will be recognized as an ordinary feed-back oscillator, and such oscillators can be made by well known methods of adjustment to produce output voltages which approximate very closely to the sine wave form. This particular type of oscillator is to be taken merely as symbolical of any suitable sine wave generator known in the art.

An output coil 7, inductively linked with the load circuit of the oscillator 1, is connected to two transformer primaries 8, 9. A secondary 11 associated with the primary winding 8 has its end terminals connected through a pair of rectifiers 12, 13 which may, for example, be high-vacuum diodes, or, alternatively, be copper oxide rectifiers or any other suitable type of rectifier. The primary winding 9 is associated with a secondary winding 14 across the terminals of which are serially connected a variable resistor 15 and a capacitor 16. The common terminal of the resistor 15 and the capacitor 16 is connected to one terminal of a primary winding 17, the other terminal of which is connected to the mid point of the winding 14. A secondary winding 18, associated with the primary winding 17, has its end

terminals connected to a pair of rectifiers 19, 21 which may be of the same general type as the rectifiers 12, 13 already mentioned. The mid point of the secondary winding 11 is connected to the mid point of the secondary winding 18, and the common terminals of the rectifiers 12, 13 are connected to one side 22 of an output circuit in which it is desired to use a wave form of the type shown in Fig. 2, the other terminal of this output circuit being connected to a line 23 connected to the common terminal of the rectifiers 19, 21.

It will be recognized that the resistor 15 and the capacitor 16 constitute a phase-displacing circuit by which the alternating voltage impressed on the primary winding 17 may be displaced to any desired degree relative to the alternating voltage impressed on the primary winding 8. By properly designing, in ways which will be evident to those skilled in the art, the size of the transformer windings above mentioned or, alternatively, by properly adjusting the resistor 15 and capacitor 16, the relative amplitudes and phase of the rectified voltage waves produced respectively by the rectifiers 12, 13 and 19, 21 may be adjusted at will. A moment's consideration of the above-described circuit will show that the rectifiers 12, 13 will produce an output voltage similar to e_1 in Fig. 1, while the rectifiers 19, 21 will produce a rectified voltage of opposite polarity displaced in phase relative to the output of rectifiers 12, 13, and hence a voltage similar to e_2 in Fig. 1 across the terminals of the rectifiers 19, 21. A voltage will be produced across the line wires 22, 23, which will have the wave form shown in the curve e_3 in Fig. 2.

In Fig. 4, I show an alternative form of network which may be connected to the output of rectifiers 12, 13 and 19, 21 in Fig. 3 to produce a wave form of the type shown in Fig. 2. When the arrangement shown in Fig. 4 is to be used, the line wire connecting the mid points of secondary windings 11 and 18 is broken. A moment's consideration will show that between the mid point of the secondary winding 11 and the common terminal 22 of rectifiers 12, 13 is produced a voltage of the form e_1 in Fig. 1, while a voltage of the wave form e_2 in Fig. 1 is produced between the output terminal 23 and the mid point of the winding 18 in Fig. 3. The terminal 22 and the line leading to the mid point of winding 11 in Fig. 3 are then connected between the terminals 24, 25 in the network shown in Fig. 4, while the terminal 23 and the mid point of the secondary winding 18 in Fig. 3 are connected, respectively, to the terminals 26 and 27 in Fig. 4. Between the terminals 26 and 27 in Fig. 4 are serially connected a pair of impedances 28, 29 which may be resistors, while a third impedance 31, which may likewise be a resistor, is connected between the mid points of the impedances 28, 29 and the line interconnecting terminals 25 and 26 in Fig. 4. A moment's consideration will show that the voltage across the terminals of the impedance 31 will be the algebraic difference of the voltages e_1 and e_2 of Fig. 1; in other words, the voltage across the impedance 31 will have the wave form e_3 shown in Fig. 2.

If a voltage of the wave form e_1 of Fig. 1 is connected across a capacitance 32 in series with a resistance 33, as shown in Fig. 5, the wave form across the resistance 33 will be of the type shown in Fig. 6. It will be noted that the downward slope of the waves shown in Fig. 6 is not rectilinear but is curved in a sense opposite to the curvature of the down slope of voltage e_3 in Fig. 2.

The degree of departure of the down slopes in Fig. 6 from rectilinearity is a function of the relative magnitudes of the capacitor 32 and the resistor 33 in Fig. 5.

Since the curvature of the down slope in Fig. 6 is the reverse of the curvature in the down slope of the voltage e_3 in Fig. 2, it will be evident that by properly proportioning the size of the capacitor 32 and the resistor 33 in Fig. 5, it will be possible to cause the curvature in the down slope of the curve e_4 of Fig. 6 to exactly compensate for the reverse curvature in the down slope of the curve e_3 in Fig. 2 if the voltages e_3 and e_4 are added together in a circuit. When this is done, a curve of the form e_5 shown in Fig. 7 in which both the up-slope and down-slope of the wave are almost exactly rectilinear will be obtained.

Fig. 8 shows a network in which the voltages of the wave form e_3 and e_4 are properly added together to obtain a wave form of the type shown in Fig. 7. Thus the output voltage e_1 between the terminal 22 and the mid point of secondary winding 11 in Fig. 3 may be connected across the terminals 34, 35 in the network shown in Fig. 8, while the output voltage e_2 appearing between the terminal 23 and the mid point of winding 18 in Fig. 3 is connected across the terminals 36, 37 in Fig. 8. Between the terminals 34 and 37 in Fig. 8 are connected a pair of impedances 38, 39 which may, for example, be resistors. The impedance 38 is shunted by a variable capacitor 41. The common terminal of the impedances 38 and 39 is connected through an impedance 42, which may be a resistor, to the line interconnecting the terminals 35 and 36.

It will be noted that the resistor 38 and capacitor 41 may be considered together to constitute an impedance.

A moment's consideration of the circuits of Fig. 8 will show that the current traversing the impedance 42 is the difference between the output currents set up therein by voltages similar to e_4 of Fig. 6 and e_3 of Fig. 1 which, as already shown, results in a wave form e_5 of the ideally rectilinear shape shown in Fig. 7. A voltage of the wave form e_5 can thus be derived from a pair of tap points on the impedance 42.

Another network is shown in Fig. 9. In this case one branch includes a parallel network 51 of an inductance 53 and a condenser 55 connected in series with a resistor 57; a second branch consists of the resistor 59 and the third branch of the resistor 61. The voltage e_1 is impressed across the branches 51-57 and 59 and the voltage e_2 across the branches 59 and 61. The sawtooth voltage e_5 having a wave form of linear negative slope is derived across the resistor 59.

With the rectified voltages e_1 and e_2 derived from a 60 cycle supply, a voltage e_5 of wave form, the negative slope branch of which is linear, was derived with components as follows in the branches of the circuit shown in Fig. 9.

Inductance 53_____ between 5 and 10 henries
 Capacity 55_____ between .33 and .66 mfd.
 Resistance 57_____ 10,000 ohms
 Resistance 59_____ 200 ohms
 Resistance 61_____ 10,000 ohms

While, in accordance with the patent statutes, I have illustrated particular embodiments of my invention, it will be recognized by those skilled in the art that the principles thereof are of broad application in ways which will be evident to them.

75 I claim as my invention:

1. In combination with a source of sine wave alternating currents, a first full-wave rectifier supplied therefrom, a second full-wave rectifier supplied with a phase-displaced sine wave voltage of the same frequency as that first mentioned, a network comprising a pair of impedances connected in series in one side of a line with a third impedance connected between the common terminal of the two first-mentioned impedances and the other side of the line, and means for connecting the output of the first-mentioned rectifier to one pair of end terminals of said network and for connecting the other said rectifier to the other end terminals of said network.

2. In combination with a source of sine wave alternating currents, a first full-wave rectifier supplied therefrom, a second full-wave rectifier supplied with a phase-displaced sine wave voltage of the same frequency as that first mentioned, a network comprising a pair of impedances of similar sign connected in series in one side of a line with a third impedance of the same sign connected between the common terminal of the two first-mentioned impedances and the other side of the line, and means for connecting the output of the first-mentioned rectifier to one pair of end terminals of said network and for connecting the other said rectifier to the other end terminals of said network.

3. In combination with a source of sine wave voltage, a first full-wave rectifier supplied from said source, a second full-wave rectifier supplied with sine wave current of the same frequency as said source, but phase displaced relative thereto, a network having four terminals, a resistor shunted by a capacitor connected in series with a second resistor between a first and a second of said terminals, an impedance connecting the common terminal of said capacitor and said second re-

sistor with both the third and fourth of said terminals, means for connecting the output of the first-mentioned rectifier to the first and third of said terminals, and means for connecting the output of said second rectifier to the second and fourth of said terminals.

4. In combination with a feed-back oscillator, a first rectifier supplied with the output voltage of said oscillator, a second rectifier fed through a phase-displacing network with the output voltage of said oscillator, a network comprising four terminals, the first and third of said terminals being connected by a channel comprising a first resistor shunted by a capacitor in series with a second resistor, an impedance connecting the common terminal of said capacitor and said second resistor with the second and fourth of said terminals, and means for connecting said first rectifier across said first and second terminals and for connecting said second rectifier across the third and fourth terminals.

5. In combination a first full-wave rectifier, having input and output terminals, a second full-wave rectifier, having input and output terminals, means for impressing sinusoidal oscillations of substantially the same wave form on said input terminals of both said rectifiers, means for displacing the outputs of said rectifiers in phase, means for combining the outputs of said rectifiers so displaced in phase in such manner that one output is subtracted from the other output and means for so distorting one of said outputs that the combined output has a wave form the negative slope branch of which is substantially linear.
